(57) **CLAIM**

The ornamental design for a display screen with graphical user interface, as shown and described.

DESCRIPTION

FIG. 1 is a front view of a display screen with graphical user interface; and,

FIG. 2 is a perspective view of the design shown in FIG. 1 on a device.

The ornamental design includes a graphical user interface. The unevenly spaced broken lines illustrate a device and the perimeters of a display screen and form no part of the claimed design. The other broken lines illustrate portions of the graphical user interface which form no part of the claimed design.
